STORE FRONT CONSTRUCTION

William Stahl, Los Angeles, Calif.

Application April 24, 1937, Serial No. 138,778

3 Claims. (Cl. 20—56.4)

My invention relates to store front constructions, and particularly, although not necessarily, to those constructions embodying inner and outer mouldings of extruded metal and between which blocks are located for supporting the pane of glass between the mouldings.

During the glass-setting operation in store front constructions of this character, the glass-supporting blocks are first adjusted along the inner moulding to those points most advantageous to minimize breakage, and then the glass is poised on the blocks while the outer moulding is applied. Heretofore, the supporting blocks have been unattached to the inner moulding and, hence, it frequently occurs that prior to or during application of the outer moulding the supporting blocks tilt transversely and occasionally longitudinally to cause the glass to fall therefrom and crack or break.

My invention contemplates the provision of a store front construction in which a connection is provided between the moulding and the supporting blocks, which is constructed and arranged to permit independent adjustment of the blocks along the length of the moulding so that they may occupy the most advantageous points of support for the glass, and in any such position of adjustment to be secured against any tilting movement and thereby form an immovable glass support which eliminates the possibility of the glass falling from the blocks during application of the outer moulding.

It is also a purpose of my invention to provide a glass-supporting block or member which is characterized by its structural form to permit of its being constructed from extruded metal and cut in any desired length, and to clear the screws or other fastening members employed for securing the inner moulding to the sill of the store front, so that unrestricted sliding adjustment of the block lengthwise on the moulding can be effected.

I will describe only one form of store front construction embodying my invention and will then point out the novel features thereof in the accompanying claims.

In the accompanying drawing:

Fig. 1 is a view showing in front elevation one form of store front construction embodying my invention, with portions of the outer moulding broken away to show the glass-supporting blocks.

Fig. 2 is an enlarged vertical sectional view taken on the line 2—2 of Fig. 1.

Fig. 3 is a fragmentary sectional perspective

view of the sill, the inner moulding, and one of the glass-supporting blocks.

In carrying out my invention I provide a store front construction having a conventional form of frame 15, the lower part of which constitutes a sill 16. Within the frame is the rough flooring which forms a bottom stop 17, while at the top of the frame are one or more top stops 18 also formed of wood.

Seated on the sill 16 and abutting the bottom stop 17 is an inner moulding M secured in place by screws 19. This inner moulding is formed of extruded metal and it comprises a vertical part 20 having at its upper edge a downwardly extending flange 21 provided with an upwardly extending lip 22 which bears against the inner side of a pane of glass 23. The moulding also includes a horizontal part 24 extending from the lower edge of the vertical part 20 and provided at its free longitudinal edge with a raised and coextensive horizontal lip 25. It is through this horizontal part 24 that the screws 19 extend into the sill 16 for securing the moulding in place.

Coacting with the inner moulding M to hold the glass 23 in place in the frame, is an outer moulding M' also formed by extruded metal and made in sections to extend around the four edges of the glass, as shown in Fig. 1. The outer moulding comprises an intermediate vertical part 26 through which screws 27 extend and pass through the vertical part 20 of the inner moulding and into the bottom stop 17 for securing the outer moulding in place.

Inclined upwardly from the intermediate part 26 is a flange 28 on which a vertical lip 29 is formed and adapted to bear against the outer side of the glass. Inclined downwardly and outwardly from the lower edge of the intermediate part 26 is a lower flange 30 provided with an inwardly extending horizontal lip 31.

Except in the instance of the bottom section of the outer moulding, the lip 31 is of such width as to abut the stops 18, but the lip for the bottom moulding section is relatively narrow and extends beneath the lip 25 of the inner moulding. This arrangement of lips 25 and 31 functions to properly align the outer moulding and definitely position it with respect to the inner moulding in a manner to lock it against upward movement thereon.

To support the glass 23 between the mouldings M and M' I provide blocks or members B at least two of which are preferably arranged adjacent the ends of the glass, as shown in Fig. 1, to minimize breakage. Each block is made of

55

extruded metal cut in any required length and comprising a flat top 32 on which the glass may directly rest or indirectly rest by the interpositioning of a cushioning pad (not shown). Legs 5 33 and 34 extend downwardly from the opposite edges of the top 32 to give to the block the cross sectional form of an inverted U.

On leg 33 is formed on its outer face with a coextensive groove 35 of dove-tail form in cross- 10 section to slidably receive a correspondingly shaped tongue 36 formed on the confronting face of the vertical part 20 of the inner moulding M. Manifestly, this connection is so constructed and arranged as to permit sliding adjustment of the 15 block on the moulding to position it at any point along the length of the moulding, and yet, the block is secured against any transverse or longitudinal tilting in any position of adjustment. Obviously, the screws 19 do not interfere with 20 sliding adjustment of the block because the spacing of legs 33 and 34 is such that they clear the screws.

Thus, once the blocks have been adjusted to the desired positions on the moulding and the 25 glass set on the blocks, there is no possibility of the blocks tilting in any direction to displace the glass therefrom, so that the outer moulding can be applied without fear of the glass falling from the blocks and cracking or breaking. It is desirable that certain of the screws 27 be extended through the blocks as shown in Fig. 2, in order to 30 secure them against lengthwise shifting on the moulding.

Although I have herein shown only one form 35 of store front construction embodying my invention including only one form of moulding, one form of supporting block, and one form of con-

nexion between the inner moulding and block, it is to be understood that various changes and modifications may be made herein without departing from the spirit of my invention and the spirit and scope of the appended claims.

I claim:

1. In a store front construction; a moulding; a tongue on the moulding; and a glass-supporting member having a groove therein slidably receiving said tongue to allow adjustment of said 10 member along the moulding and yet secure the member against transverse movement relative to the moulding.

2. In a store front construction; a sill; a moulding on the sill having a horizontal part 15 and a vertical part; fastening members extending through the horizontal part and into the sill for securing the moulding to the sill; a glass-supporting member adjustable along the horizontal part and open at its bottom to clear the fastening members; and a connection between the vertical part and said member for so securing the two together that the member is retained against transverse movement yet permitting adjustment thereof along the moulding.

3. In a store front construction; a sill; a moulding on the sill having a horizontal part and a vertical part; fastening members extending through the horizontal part and into the sill for securing the moulding to the sill; a glass-supporting member adjustable along the horizontal part and open at its bottom to clear the fastening members; a tongue longitudinally on the vertical part; and a groove longitudinally in the confronting side of said member slidably receiving the tongue.

WILLIAM STAHL.
